UNITED STATES PATENT OFFICE.

CHARLES F. PFLANZE, OF ST. LOUIS, MISSOURI.

WEB-SEVERING DEVICE.

Application filed December 17, 1919. Serial No. 345,605.

To all whom it may concern:

Be it known that I, CHARLES F. PFLANZE, a citizen of the United States of America, a resident of the city of St. Louis, in the State of Missouri, have invented certain new and useful Improvements in Web-Severing Devices, of which the following is a full, clear, and exact description, reference being had to the accompanying drawings, forming a part 10 of this specification.

This invention relates to improvements in severing devices, and more particularly to a device adapted to sever a traveling web of material, such as paper or the like. One of 15 the objects of the invention is to provide a simple and positive severing means whereby a traveling web of paper may be accurately divided into uniform sheets or strips. The device herein shown may be used to 20 sever long webs of different kinds of material, and it is especially adapted for use in the manufacture of window envelopes having transparent patches at the window openings. A traveling web of thin, transparent 25 paper may be acted upon by the new device, so as to provide the small transparent patches.

With the foregoing and other objects in view, the invention comprises the novel construction, combination and arrangement of parts hereinafter more specifically described and illustrated in the accompanying drawings wherein is shown the preferred embodiment of the invention. However, it is to be 35 understood that the invention comprehends changes, variations and modifications which come within the scope of the claims hereunto appended.

Fig. I is a vertical section illustrating the 40 combined feeding and severing device.

Fig. II is a view similar to Fig. I showing the parts in different positions.

Fig. III is a front elevation of the device shown in Fig. I.

Fig. IV is a side elevation, on a small scale, showing the driving mechanism.

Fig. V is a detail view of the roll provided with a blade for tightening the web of paper.

Fig. VI is a detail view of the roll having

a severing blade onto which the paper is tightened.

In Figs. I and II, A designates a web of paper which is to be cut into small sections A'. To illustrate the invention I have shown paper feeding rolls 1, 2 and 3, each fixed to a central shaft 4. Bearings 5 are slidably mounted in side frames 6 to receive the shafts 4 which extend from rolls 1 and 3. Springs 8, acting upon bearings 5, tend to force the rolls 1 and 3 toward the rolls 2, and the traveling web of paper (Fig. I) is thus held at two separated points by the pressure of the two separated feeding rolls 1 and 3 on the periphery of roll 2. All of these rolls 60 are driven simultaneously at the same peripheral speed by means of pinions 9 (Fig. IV), fixed to the shafts 4, and a drive wheel 10 meshing with one of the pinions.

The severing device preferably comprises 70 severing blades 12 located in longitudinal grooves 13 in the roll 2, and secured by means of screws, as shown in Fig. I. These severing blades 12 extend from diametrically opposite points on the periphery of roll 2, 75 and they are preferably provided with straight serrated cutting edges (Fig. VI) which lie parallel with the axis of the roll. Web-tightening blades 14 are mounted in longitudinal grooves in the roll 3 and secured 80 by means of screws (Fig. I). Each of these web-tightening blades 14 (Fig. V) preferably has a smooth, dull edge adapted to engage and tighten the paper, and this dull edge is preferably inclined from the middle 85 to the ends of the blade, so as to gradually tighten the paper on the serrated edge of the severing blade 12. Each roll 2-3 is grooved to receive the blade projecting from its companion roll, and the peripheral face 90 of roll 1 is preferably mutilated, or cut away, to permit the severing blades 12 to pass freely under the roll 1 (Fig. III).

When the rolls occupy the positions shown by Fig. II, a severing blade 12 lies adjacent 95 to the roll 1, and springs 8 tend to force said roll 1 toward the roll 2, but the spring-pressed bearings 5, in which said roll is mounted, then engage the bottom walls of the guideways for the bearings, so the 100

5 springs 8 will not force the roll 1 onto the severing blade 12. The peripheral portion of roll 1 is preferably formed by a body of rubber, oblong in cross section, and having oppositely disposed concentric faces adapted to cooperate with roll 2 to feed the paper and to prevent slippage thereof during the severing operation.

10 To understand the action of the severing device (Fig. I), it is important to observe that the traveling web of paper A—A' is firmly held at two separated points, where it contacts with the rolls 1 and 3, and immediately before the severing operation the 15 paper is bowed between these holding points so as to overlie and engage the sharp serrated edge of severing blade 12. Since the paper is firmly held to prevent slippage on opposite sides of severing blade 12, said 20 paper may be severed if it is tightly drawn onto the edge of blade 12. This action is accomplished by the tightening blade 14, which moves transversely of the path of the paper and eventually enters groove 13, in 25 which blade 12 is mounted. Obviously, the paper which cannot slip will be either cut or torn by the action of tightening blade 14, and since the paper is tightened on the sharp serrated edge of blade 12, it will be 30 positively severed at said edge. It may be interesting to observe that this positive severing device will properly perform its function even though the blades 12 and 13 are not accurately located in precise relative positions, and in this respect it differs from ordinary shearing devices, wherein two sharp blades cooperate with each other. In an ordinary shear the two blades must contact with each other in a particular manner, 35 but in the new device herein disclosed the traveling web of paper is merely tightened on the sharp edge of a traveling severing blade.

I claim:

40 1. In a device for feeding and severing a traveling web of paper, a rotary severing blade movable with the traveling web, and a rotary tightening blade also movable with the traveling web, said blades being engaged 45 with opposite sides of the traveling web so that the edge of the rotary tightening blade will intersect the path of said severing blade to tighten said web on the severing blade, said tightening blade having a smooth edge 50 engaging the web and said severing blade being provided with a serrated edge which engages the web.

55 2. In a device for feeding and severing a web of paper, a pair of feed rolls disposed 60 on opposite sides of the paper, a severing blade projecting from the periphery of one of said feed rolls, and a web tightening blade projecting from the periphery of the other feed roll, the edge of said tightening blade 65 being arranged to intersect the path of said

70 severing blade, so as to tighten the web and force it onto said severing blade.

75 3. In a device for feeding and severing a web of paper, a pair of feed rolls disposed on opposite sides of the paper, a severing blade projecting from the periphery of one of said feed rolls, and a web tightening blade projecting from the periphery of the other feed roll, the edge of said tightening blade being arranged to intersect the path of said severing blade, so as to tighten the web and force it onto said severing blade, each of said rolls being recessed to receive the blade on the other roll.

80 4. In a device for feeding and severing a web of paper, rotary rolls including oppositely disposed feed rolls whereby the web is fed and held to prevent slippage at two separated points, a severing blade extending from one of said rolls, and a web-tightener 85 extending from another of said rolls, said severing blade and web-tightener being disposed on opposite sides of the traveling web, and the edges of said blade and said web tightener being arranged to travel in intersecting paths so that the tightened web will be forced onto the severing blade.

90 5. In a device for feeding and severing a web of paper, a group of rotary feed rolls whereby the web is fed and held to prevent slippage at two separated points, a severing blade extending from the periphery of one of said rolls, said severing blade having a serrated edge adapted to engage the web between said separated points, and a tightening blade extending from the periphery of another of said rolls and having a smooth edge adapted to engage the web between said separated points, said blades being on opposite sides of the path of the traveling web and the edges of said blades being movable in intersecting paths so that the tightening blade will force the tightened paper onto the serrated edge of the severing blade.

95 6. In a device for feeding and severing a traveling web of paper, feed rolls whereby the traveling web is held at separated points, a blade arranged to engage the traveling web between said separated points, and a web-tightening member whereby the web is tightened on the edge of said blade, said feed rolls including a rotary roll having a peripheral face whereby the web is held at one of said points during the severing operation and released during the intervals between the severing operations.

100 7. In a device for feeding and severing a traveling web of paper, holding members whereby the traveling web is held at separated points, a blade arranged to engage the traveling web between said separated points, and a web-tightening member whereby the web is tightened on the edge of said blade, said holding members including a feed roll 105 having a non-circular peripheral face where-

by the traveling web is alternately held and released at one of said points.

8. In a device for severing a traveling web of paper, holding members whereby the traveling web is held at separated points, a severing blade adapted to engage and deflect the traveling web between said separated points, and a tightening blade cooperable with the first mentioned blade to tighten and sever the deflected web between said points, said holding members including feed rolls whereby the traveling web is held while the blades cooperate with each other and released to permit free deflection of the web and said severing blade being extended from the periphery of one of said feed rolls to separate a portion of said web from said periphery.

9. In a device for severing a traveling web of paper, holding members whereby the traveling web is held at separated points, a blade adapted to engage and deflect the traveling web between said separated points, and a blade cooperable with the first mentioned blade to tighten and sever the deflected web between said points, said holding members including feed rolls, one of which is provided with a non-circular peripheral face, whereby the traveling web is held while the blades cooperate with each other and released to permit free deflection of the web.

10. In a device for severing a traveling web of paper, rotary feed rolls whereby the traveling web is held at separated points, a severing blade adapted to engage and deflect the traveling web from the periphery of one of the feed rolls at a point between said separated points, and a blade cooperable with the first mentioned blade to tighten and sever the deflected web between said separated points, the edges of said blades being movable in intersecting paths, and said rotary feed rolls being provided with web-engaging faces whereby the traveling web is alternately released and held at one of said points.

11. In a device for severing a traveling web of paper, rotary feed rolls whereby the traveling web is held at separated points, a blade adapted to engage and deflect the traveling web between said separated points, and a blade cooperable with the first mentioned blade to tighten and sever the deflected web between said points, said blades being movable in intersecting paths, and one of said rotary feed rolls being provided with a non-circular peripheral face whereby the traveling web is held while the blades cooperate with each other and released to permit free deflection of the web.

12. In a device for severing a traveling web of paper, three rotary feed rolls, one of said feed rolls having a peripheral face cooperating with the peripheries of the other two feed rolls to grip and feed the web at

two separated points, and severing elements projecting beyond the peripheries of two of said rolls to sever the web between said points.

13. In a device for severing a traveling web of paper, three rotary feed rolls, one of said feed rolls having a peripheral face cooperating with the peripheries of the other two feed rolls to grip and feed the web at two separated points, a blade projecting beyond the periphery of one of said rolls to engage and deflect the traveling web between said points, and a blade projecting beyond the periphery of another of said rolls and cooperating with the first mentioned blade to tighten and sever the web between said points.

14. In a device for severing a traveling web of paper, three rotary feed rolls, one of said feed rolls having a peripheral face cooperating with the peripheries of the other two feed rolls to grip and feed the web at two separated points, a blade projecting beyond the periphery of one of said rolls to engage and deflect the traveling web between said points, and a blade projecting beyond the periphery of another of said rolls and cooperating with the first mentioned blade to tighten and sever the web between said points, said blades being movable in intersecting paths, and one of said rolls having a non-circular peripheral face whereby the web is alternately held and released.

15. In a device for severing a traveling web of paper, three rotary feed rolls, one of said feed rolls having a peripheral face cooperating with the peripheries of the other two feed rolls to grip and feed the web at two separated points, a blade projecting beyond the periphery of one of said rolls to engage and deflect the traveling web between said points, and a blade projecting beyond the periphery of another of said rolls and cooperating with the first mentioned blade to tighten and sever the web between said points, the respective blades being secured to two of said rolls, and the other roll having a non-circular peripheral face permitting rotation of one of said blades.

16. In a device for feeding and severing a traveling web of paper, holding members whereby the traveling web is held at separated points, a blade arranged to engage the traveling web between said separated points, and a web-tightening member whereby the web is tightened on the edge of said blade, said holding members including rotary feed rolls cooperating with each other to hold the paper at said separated points, said blade being secured to and carried by one of said feed rolls and said web-tightening member being secured to and carried by another of said feed rolls.

17. In a device for severing a traveling web of paper, holding members whereby the

traveling web is held at separated points, a blade adapted to engage and deflect the traveling web between said separated points, and a blade cooperable with the first mentioned blade to tighten and sever the deflected web between said points, said holding members including a rotary feed rolls cooperating with each other to hold the paper at said

separated points, said severing blade being secured to and carried by one of said feed rolls, and said tightening blade being secured to and carried by another of said feed rolls. 10

In testimony that I claim the foregoing I hereunto affix my signature.

CHARLES F. PFLANZE.
